EUGENE W. KELSEY, OF COLLIERVILLE, TENNESSEE.

HAY-PRESS.

No. 825,132.

Specification of Letters Patent.

Patented July 3, 1906.

Application filed May 4, 1905. Serial No. 258,807.

To all whom it may concern:

Be it known that I, EUGENE W. KELSEY, a citizen of the United States, and a resident of Collierville, in the county of Shelby and State 5 of Tennessee, have invented a new and Improved Hay-Press, of which the following is a full, clear, and exact description.

My invention relates to hay-presses of that type known as a "rebounding-plunger" press. 10 The purpose of the invention is to provide a simple, durable, effective, and economic form of press operated by horse-power, and to provide a single double-cam-faced operating-lever for the plunger-shaft which has a 15 direct action and which operates with the least possible friction and which also acts upon the plunger-shaft almost immediately upon its return from its pressing-stroke.

Another purpose of the invention is to provide an improvement in the folder wherein it is rendered spring-controlled and to so construct the return mechanism for the plunger that the tension of the controlling-spring can be made strong or weak as occasion may demand. 25

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures. 30

Figure 1 is a sectional side elevation of the improved press. Fig. 2 is a plan view of the press. Fig. 3 is a plan view of a portion of the operative mechanism for the plunger, drawn upon an enlarged scale and illustrating 35 the plunger-shaft as partially pushed to the rear. Fig. 4 is a transverse section taken on the line 4-4 of Fig. 3, being also drawn upon an enlarged scale. Fig. 5 is a detail sectional view of a portion of the baling-chamber and a transverse section through the folder. Fig. 6 is a plan view of the plunger and its shaft and a slightly-modified form of operating-lever, and Fig. 7 is a side view of the delivery end of the press. 40

A represents the body of the press. In the construction of this body a bottom 10 is employed and a top 11, which extends to the back, but stops short at the front, so that the front upper portion of the body is open. 45 Side pieces 12 are secured to the top and bottom at the front open portion of said body,

forming thereby a baling-chamber B, open at the front as well as at the top, and the said side pieces 12 extend rearward beyond the forward end of the top 11, as is clearly shown 60 in Fig. 1. Flanged side pieces 12^a extend down from the top at the rear of the complete side pieces 12, and corresponding flanged side pieces 12^b extend up from the bottom; otherwise the rear portion of the 65 body is open.

The body is braced and strengthened by placing cross-pieces 14 at the top and at the bottom, which cross-pieces 14 are located at the rear ends of the body at its central portion and at its forward portion. The upper forward cross-piece 14 is made to rest upon a front section 11^a of the top of the body, as is shown in Fig. 1, which front section 11^a extends from one side piece 12 to the other. 70 The said cross-bars 14 are connected by brace-rods 15 at their ends, located at the outside of the body; but I desire it to be understood that additional means may be employed for strengthening the body—as, for 75 example, is shown at 15^a in Fig. 2.

A series of apertures 16 is made in the sides 12 of the baling-chamber B adjacent to the rear open portion of the said chamber, and keeper-springs 17 are secured at one of their 80 ends to the outside of the side pieces 12 adjacent to each slot or aperture 16. The heads 17^a of these springs, which are of triangular construction, as is shown in Fig. 2, extend into the baling-chamber B through the 85 said slots.

The forward end of the top 11 of the body A is given a downward and rearward inclination, as is shown in Figs. 1 and 5, and at this point a folder 19 is located. This folder is 90 made of metal and comprises a horizontal upper body-section 19^a, a downwardly and rearwardly extending lip 19^b at the forward end of the body-section, and arms 19^c, which extend rearwardly from the body-section and 95 are pivoted on the said body, as is clearly shown in Fig. 5.

A cross-bar 14, which extends over the top 11 adjacent to its forward end, is provided with a chamber 21 in its under face and extends over the pivoted arms 19^c of the folder. 100 In this chambered portion of this said intermediate cross-bar 14 springs 22 are located, which have bearing upon the pivoted arms 19^c of the holder, serving to hold the folder 19 in its lower or normal position (shown by positive lines in Fig. 5); but as the plunger

to be hereinafter described operates in the said baling-chamber B it lifts the folder 19 to the dotted position shown in Fig. 5 when the said plunger is about finishing its pressing-stroke.

At the rear end of the body A plates 23 are hinged to the inner faces of the top and bottom sections 11 and 10, as is shown in Fig. 1, and springs 24 are made to bear against the rear or free ends of the said plates 23. These plates are adapted to further compress a bale as it leaves the said body A.

The lower sills of the body A extend beyond its forward open end, as is shown at 13 in Figs. 1 and 2, and extension-sills 25 are secured to the sills 13 in any suitable or approved manner, which extension-sills are carried as far to the front as may be desired. A platform 26 is constructed on the forward end portions of the extension-sills 25, as is shown in Fig. 2.

A rear axle 22 is secured to the bottom portion of the body A below the baling-chamber B, and wheels 23^a are removably placed on the said axle 22. From the forward end of the platform 26 a bracket 27 is projected, to which the forward truck 28 is pivoted, carrying the forward wheels 29, which are likewise removable, as when the press is in use the axles rest upon the ground, as is shown in Fig. 1, so that the horse or team employed in the operation of the press may readily step over the extension-sills 25 and parts carried thereby.

35 A bearing 30 is secured upon the platform 26 near its forward end and about centrally between its sides, and in this bearing the pivot-pin for an operating-lever C is mounted, which pivot-pin passes through the central portion of the said lever. This lever C is provided with cam-surfaces 31 and 32 at its ends, facing in opposite directions, and the said cam-surfaces are more or less semi-elliptical, and there is more or less of a depression where they meet the straight lines of the lever C.

Draft-arms 33 are secured to the operating-lever C at its upper portion—one near each end—and the free ends of the said draft-arms 50 are brought together and are secured in any suitable or approved manner, and where the said draft-arms come together a clevis 34 is attached, to which a team or a single horse is attached, as occasion may demand. In 55 front of the said bearing 30 a brake-spring 35 is secured on the platform 26, which brake-spring is secured at its left-hand end to the said platform, its right-hand end portion being free and upwardly curved and then horizontally carried toward the right-hand side of the platform, as is shown in Figs. 2 and 3.

A plunger 36 is adapted to slide in the baling-chamber B. This plunger 36 has its right-hand side 37 more or less beveled from 65 its inner face in direction of the left-hand

side, as is particularly shown in Fig. 6, and a socket 38 is formed on the forward face of the said plunger 36, preferably made of metal and comprising four members, and into this socket 38 the rear end of the plunger-shaft 70 39 is entered and secured.

At the forward end of the plunger-shaft 39 a friction-roller 41 is mounted, and at the lower face of said forward end a cross-head 42 is secured or made integral therewith. This 75 cross-head 42 is provided with two horizontally-aligning slots 42^a, as is best shown in Fig. 4. Guide-rails 43 are made to freely pass through these slots 42^a in the said cross-head 42, the said guide-rails being elevated from the platform 26, upon which they are located. These guide-rails 43 extend from the right-hand side of the platform at a point just in front of the right-hand cam of the operating-lever C when said operating-lever is in its normal position (shown in Fig. 2) and the said 80 guide-arms 43 are curved in direction of the left-hand side of the platform, terminating at or about its center. The guide-rails 43 are connected at their ends, so that the plunger-shaft 39 is compelled at its forward end to follow the said guide-rails 43 and cannot leave them.

At the outer face of the right-hand extension-sill 25 a horizontal bracket 44 is secured 95 in any suitable or approved manner, and this bracket extends parallel with the said sill and is provided with a longitudinal slot 45, as is shown in Fig. 3. A block 46 is made to travel in the said slot 45 of the bracket 44, as is 100 shown in Figs. 3 and 4, and a screw-rod 47, which is preferably integral with the block, is made to enter an interiorly-threaded tube 48. A spring 49 is coiled around the said tube and the said screw rod or bar 47, having bearing 105 at one end against the rear face of the block 46, being secured at its opposite end to the right-hand side of the plunger-shaft 39, and the said spring 49 is likewise secured to the tube 48 at a convenient point in its length, 110 preferably at its forward end. This spring is placed under compression when the plunger is forced rearwardly in the baling-chamber B by the action of the operating-lever C, and when the plunger-shaft 39 is relieved from 115 engagement with a cam on the said operating-lever C the spring 49 acts to force the said shaft 39 and the plunger 36 to their normal positions, at which time the plunger is at the forward end of the baling-chamber B, as is 120 shown in Fig. 1; but the said spring does not commence to act until the plunger is within six or eight inches of the finish of its rearward stroke.

The folder 19 serves to prevent the hay at 125 the top of a bale from crowding back again into the baling-chamber, and the springs 17 serve the same purpose with respect to the side portions of the compressed mass of hay.

In Fig. 6 I have illustrated a slightly-modi- 130

fied form of the operating-lever C, which operates, however, in the same manner. In the modified form of the operating-lever a body-block 50 is employed of rectangular shape, 5 and upper and lower bars 51, of metal, are made to extend diagonally the length of the said block 50 and beyond its ends. From opposite sides of the bars 51 near their ends ears 52 are projected, and between these ears 10 52 friction-rollers 53 are mounted to turn, so that these friction-rollers 53 are at opposite sides of the block 50. Between the end portions of the bars 51 larger friction-wheels 54 are mounted to turn so that the smaller friction-rollers 53 and adjacent larger friction-rollers 54 accomplish the same result as the cam-surfaces 31 and 32 shown in the other views and represent practically the same construction. The draft-bars 33 are secured 15 to the block 50 at its upper face, as is also shown in Fig. 6. In this figure instead of the friction-roller 41 at the end of the plunger-shaft the said shaft is provided with a bend or crank-arm 40, with which the rollers of the 20 operating-lever engage.

The cams shown in Figs. 2 and 3 can be made in one piece in any approved form, so that the relative positions of the antifriction-rollers and pivot are preserved.

30 In operation, as the draft arms or bars 33 are moved by means of a team or otherwise, the operating-lever C is made to turn upon its pivot, and supposing the plunger-shaft 39 to be in its normal position, (shown by positive 35 lines in Fig. 2,) having its friction-roller 41 in engagement with the cam 31, where it connects with the lever C as the said lever is turned, the cam-surface 31 will force the shaft 39 rearward, and said shaft will cause 40 the plunger 36 to slide also rearward in the baling-chamber B, compressing the material fed to said chamber. When the plunger 36 has reached a true horizontal position about midway between the extension-sills 25 and the 45 end of the cam 31 engages with the roller 41 of the plunger-shaft 39, as is shown by dotted lines in Fig. 2, a further swinging movement of the lever will permit the plunger-shaft 39 and attached plunger to move quickly forward by the action of the spring 49, as such 50 spring was placed under tension as the plunger was forced rearward on its working stroke. This forward movement of the plunger-shaft would tend to accelerate the speed of the operating-lever C, since the roller of the plunger-shaft would travel along the plain body-surface of the lever, and in order to slightly 55 check this inclination to a sudden movement on the part of the lever the brake-spring 35 60 is provided, which offers a slight resistance to the lever as the forward end of the plunger-shaft 39 reaches its forward position for engagement with the other cam-surface 32 at the opposite end of the lever C, so that it will 65 be observed in the operation of this lever one

cam acts to press the plunger rearward, then releases the plunger, and almost immediately the other cam acts in like manner. Owing to the slight depression where the cam-surfaces 31 and 32 meet the plain surfaces of the 70 lever C, the cams are prevented from slipping and always act first at their initial points on the said plunger-shaft. The operation of the form of operating-lever shown in Fig. 6 is identical with that which has been described 75 with reference to the lever having the cam-terminals.

It will be observed that as the plunger-shaft 39 is initially inclined to the right-hand side of the machine the plunger 36 in its 80 normal position has a slight cant in the baling-chamber, and the bevel 37 is provided at the right-hand side of the plunger 36 in order that the said plunger may assume such position without frictional engagement with the 85 side walls of the baling-chamber.

In Fig. 7 I have illustrated a tension device E, which I preferably employ for connecting the upper and lower members of the press at its delivery end. This device consists of two 90 parallel and substantial short bolts 55 and 56, having heads at one end and nuts 57 at the other end, and these bolts are loosely passed through end cross-heads 58 and 59 and an intermediate cross-head 60. A main bolt 61 is 95 loosely passed through the central portion of the lower cross-head 59 and the intermediate cross-head 60 and also through the bottom of the press and is provided with a nut 62 at its lower end. A second main bolt 63 is passed 100 through the upper cross-head 58 and through the upper portion of the press, being provided with a nut 64 at its upper end. A spring 65 is coiled around the lower bolt 61, which spring has bearing against the lower and intermediate cross-heads. Thus the press is 105 always under tension at its delivery end, and the bale is also subjected to tension upon leaving the press. The tension may be increased or decreased, as desired, by adjusting 110 the said nuts.

Having thus described my invention, I claim as new and desire to secure by Letters Patent—

1. In a hay-press, a body portion provided 115 with a baling-chamber, a plunger mounted to slide in said chamber, a forward extension from the said body, a lever centrally pivoted upon said forward extension, provided with cam-surfaces at its ends facing in opposite 120 directions, which cam-surfaces meet the plain side edges of said lever more or less abruptly, draft-arms secured to the said lever between its ends, a shaft secured to the said plunger, having a roller at its outer end, an apertured 125 cross-head secured to the bottom portion of the said plunger-shaft at its outer end, and segmental guide-rails secured to the said extension, which guide-rails freely pass through the apertures of the cross-head, and a tension 130

device for the said plunger-shaft, adapted to return the same to normal position.

2. In hay-presses, a body provided with a baling-chamber, a plunger mounted to slide in said chamber, an extension from the forward portion of said body, an operating-lever having oppositely-facing cam-surfaces at its ends, draft-arms secured to said operating-lever, a shaft secured to the plunger, normally extending in direction of the right-hand side of the said extension, being provided with a friction-roller at its outer end, an apertured cross-head secured to the under face of the said plunger-shaft at its outer end, segmental guide-rails secured to said extension and loosely passed through the apertures in the said cross-head, a spring attached to said plunger-shaft and to a point on the said extension, and means for tightening and loosening said spring, to increase and decrease its strength in operation.

3. In hay-presses, a body provided with a baling-chamber, a plunger mounted to slide in the said chamber, an extension from the forward portion of said body, an operating-lever having oppositely-facing cam-surfaces at its ends, draft-arms secured to said operating-lever, a shaft secured to the plunger, normally extending in direction of the right-hand side of said extension, being provided with a friction-roller at its outer end, an apertured cross-head secured to the under face of the said plunger at its outer end, segmental guide-rails secured to the said extension and loosely passed through the apertures in the said cross-head, a bracket secured to the right-hand side of the extension, which bracket has a slot therein, a block held to slide in the slot of the said bracket, a screw carried by said block, a tube interiorly threaded to receive the said screw, and a spring attached at one end to the plunger-shaft and to said tube, which spring coils around the tube and around the said screw, engaging with the rear face of said block, for the purposes set forth.

4. In a hay-press, the combination with a baling-chamber, a plunger in the said chamber, and means for operating the plunger, of a screw-rod having guided and sliding movement, an interiorly-threaded tube in which

the screw-rod projects, and a spring surrounding the tube, said spring being secured to the plunger-shaft and to the tube.

5. In a hay-press, the combination with a baling-chamber, a plunger in said chamber, and means for operating the plunger, of a slotted bracket at one side of the baling-chamber, a block mounted to slide in the slot of the bracket, a screw-rod secured to the block, an interiorly-threaded tube in which the screw-rod projects, and a spring surrounding the tube and rod and having one end secured to the plunger-shaft, the spring being also secured to the tube. 65

6. In a hay-press, the combination of a baling-chamber, a spring-pressed plunger in the said chamber, a block on the under side of the outer end of the plunger-shaft and provided with slots, segmental guide-bars working in the slots of the said block, a revolving lever having cam-faces at its ends extending on opposite sides of the said lever, and means for operating the lever. 70

7. In a hay-press, the combination with a baling-chamber, a plunger in said chamber, and means for operating the plunger, of a spring connected with the follower, and means whereby the spring is caused to exert force upon the plunger only when the said plunger has nearly completed its rearward stroke. 75

8. In a baling-press, the combination with a baling-chamber, a plunger in said chamber, and means for operating the plunger, of two members adjustable one upon the other, one member having guided and sliding movement, and a spring secured to the plunger-shaft and to one of the said members. 85

9. In a hay-press, the combination with a chamber, a plunger in the chamber, and means for operating the plunger of a sliding member, and a spring having one end connected with the follower and its other end connected with the sliding member. 90

In testimony whereof I have signed my name to this specification in the presence of two subscribing witnesses.
